[57] ABSTRACT

A knockdown flying form quickly assembled and disassembled at a building site and providing as a unit a unitary form having guided metal to metal roll-out contact with adjustable form supports for pouring successive floor slabs of reinforced concrete. Laterally spaced I-beams permanently trimmed with wood strips support equally spaced saddle hangers that are interconnected by laminated wood joists whose ends vertically overlap and square the I-beams as well as provide a low profile with their vertically spaced rails disposed well above the upper and lower flanges, respectively, of the I-beams. The metal members have rigid wood-to-steel engagement at all points of readily releasable interengagements.

FIG. 10

FLYING FORM

BACKGROUND OF INVENTION

Many problems confront the building industry with the conventional flying forms with regard to ready-assembly, economy, stability and reusability. Knock apart wood assemblies have short lives and the waste of time and material is high. Welding and flame cutting of steel generally involved at a building site are extensive. Moreover, once assembly-welded and then disassembled by flame cutting, the parts are not the same for ready assembly at a new site.

Disassembly of flying forms is necessary because of their size. Even if light enough, they can only be transported intact, from site to site, by helicopter if expense is no objection. Delays incurred because of needed repairs are quite expensive where a timed building sequence is interrupted. Welded metal-to-metal securements are difficult and time consuming to repair. With the likelihood of such contingencies arising their cost is reflected in bid prices. In both events the building cost is substantially high even though savings are being accomplished with conventional flying forms over earlier practices.

Furthermore, difficulty has been experienced with fastening plywood flooring to steel beams as well as securing the steel beams to I-beams for a knockdown assembly. This is particularly true when endeavoring to minimize the overall height of the formwork by a substantial vertical compacting of the coacting elements.

It is also to be noted that since formwork plywood panels must be supported on minimum joist centers related to the thickness of the floor slab to be poured, the weight of the formwork is materially greater with metal joists. In fact, motorized lifts are generally required to handle the metal joists individually during assembly as distinguished from being light enough to be dropped in by hand, as in the present invention, and bolted into place without need for a lift or crane handling them.

SUMMARY OF INVENTION

The present invention relates to site assembled and disassembled formwork for the pouring of successive concrete floor slabs supported on rollout column supports which are more particularly described in Mocny, et al., application Ser. No. 322,969. Once assembled the formwork sections are used as a unit supported for pouring one floor slab and then lowered and rolled out horizontally by a crane, lifted and again set in place on formwork supports above the first slab for the pouring of the next slab. Hence, they are referred to as flying forms.

Although channel beams can be used in the flying forms in the present invention because the beams are restrained throughout their length against lateral flexure and rotation, it is preferred to use rolled steel I-beams with moderately wide flanges on the two main beams because of their lateral stability with assembled parts for knockdown storage or shipment between building sites. They furthermore assure a self-standing orientation, or posture, during assembly and dismantling at a building site.

The steel I-beams upon assembly are positioned exactly in their ultimate working position and pairs of facing side saddle brackets are spaced along and securely supported in depending position from the top of the beams. They in turn receive the ends of comparatively

light laminated wood joists formed in an "I" cross-sectional configuration with top and bottom rails connected by a vertical web. The joists are of exact length, and their square ends drop into place in the saddle brackets with the top and bottom rails disposed substantially above the respective upper and lower flanges of the main beams. The joists ends square the opposing sides of the I-beams.

When assembled the ends of the joists are not only disposed as mentioned but are also bolted to the brackets to serve dually as compression and tension members that unitize the assembly for handling by a crane with spread lift cables temporarily secured to the corners of the form to roll it out, to fly it, and position it for the next floor slab pouring.

The brackets project laterally at an elevation between flanges and are preferably secured by bolts to the main beams. Then when the beams are transported knocked down they can rest side by side with the brackets on the one side of one beam nested in the channel of the adjacent beam.

An object of the invention is to provide a vertically compacted profile so that the form may be lowered a long distance onto roll-out roller supports thereby not only avoiding horizontal movement interference with the bottom of the floor slab completed above it but permitting depending protuberances or reinforcing shapes to be integrally cast and used by the contractor in the design of the building.

A further object is to provide light flying forms which can be adjusted initially into final orientation on pre-levelled rollers provided in Mocny, et al., Ser. No. 322,969 and then contacted thereafter by the stationary shoe supports with a given number of turns of a winged nut for proper final elevation, it being much easier to determine the levelling of the form supports before the form is lowered into place.

Additionally, joists of exact length ready for assembly are used, but if any shortening thereof is required it is easily done by a power saw as distinguished from cutting metal and welding it as required with fabricated metal joist. Moreover, the light joists are easier to handle without a power lift. Also the joists can be inverted from time to time to utilize both rails in nailing and the longevity thus expected can extend over a period of time involving the pouring of over a hundred floors. If a joist is weakened by damage, it is easily repaired on the job even though already in working position.

IN THE DRAWINGS

FIG. 1 is a plan view of a flying form as placed in working position between two rows of a plurality of support columns defining a roll-out path.

FIG. 2 is a plan view of a couple of flying forms as placed in working position between successive rows of support columns defining at least two roll-out paths with a space between the forms intermediate two columns.

FIG. 3 is a segmented end view of a flying form as assembled on levelling blocks before being lifted into place as shown in FIGS. 1 or 2.

FIG. 4 is a sectional view from below the flying form as indicated at line 4-4 in FIG. 2 showing the formwork supports on opposite sides of a support column.

FIG. 5 is a view from below as indicated at line 5-5 in FIG. 2 showing the formwork support screw jack as engaged by the I-beams of the formwork.

FIG. 6 is a perspective view partially in section showing the assembled relation of the joists with the I-beams.

FIG. 7 is a sectional view taken on the line 7—7 in FIG. 6.

FIG. 8 is a sectional view taken on the line 8—8 in FIG. 7.

FIG. 9 is a sectional view taken on the line 9—9 in FIG. 7, and

FIG. 10 is an exploded view of the joist and bracket support joint shown in FIG. 6.

members supports narrow veneer panels 90 level with the other veneer panels 84. The lay-in frame 92 is then freed to be removed when one of the forms lateral thereto is lowered its full predetermined distance. This permits one edge of the narrow frame 92 to swing down at that side and free itself for removal intact for reuse.

After the pouring and the setting of the floor slab, the two formwork assemblies are unbolted and the one that is to be flown first is lowered all the way by the screw jacks 14 including the winged nut to ultimately rest on the rollers. This frees the narrow panel for removal whereupon the sling cables 88 are fished through the vertical space thus provided between the floor slab and form and attached to the eyebolts 17. The flying form is then rolled out until it is crane borne and lifted to its new position. This procedure is repeated for the remaining forms.

The invention will be further understood in view of further advantages attained thereby generally relating to longevity and easy usability.

Hardwood filler blocks and wide rails:

- a. Carry the weight localized on wide top and bottom rails at their ends to save the web against buckling and damage;
- b. They protect with substantial thickness the web against side sway and twisting as well as bumps encountered by the head rail above the side supports of the saddle as when plywood panels are slid into place;
- c. They coat with plywood floor panelling to strengthen against "tear outs" when the formwork is being handled as a "flying form" by a crane;
- d. Wooden joists exactly space the steel I-beams for accuracy throughout long use in the successive pouring of floor slabs;
- e. They provide nail receiving supports for securing the plywood with either rail disposed upwardly, thereby doubling longevity.

The arrangement shown with the bottom rail located 40 above the bottom flange and the top rail above the scantling:

- a. Substantial vertical compaction and greater joint areas are attained;
- b. Exposes the bottom I-beam flange for metal-to-metal roll out as guided by side guides on the roll-out support, without any side guides extending above the bottom flange interfering with the bottom rails;
- c. Metal-to-metal roll-out contact has many advantages over the old metal roller-to-wood beam arrangement. Narrow wood beams would not be strong enough;
- d. The drop of the I-beams by the screw jacks can be very substantial so that the formwork upon roll-out clears the bottom of the floor slab and any irregularities or depending protuberances intentionally provided on the lower surface thereof;
- e. Parallel I-beams provide for easy roll-out;
- f. Channel beams can be used if clearances are tight;
- g. Joists cross brace the I-beams against rotation or bowing under load;
- h. In storage or transportation lateral resting of brackets on one I-beam in the channel of the next beam beside it provides compactness for shipping or storage with the brackets left in place for repeated uses.

The arrangement shown with the top rails above the scantling provides vertical space within which to support the ends of lumber on the scantlings to carry veneer panels bridging the space between laterally adjacent formwork members across lateral bays between support columns.

What is claimed is:

1. Prefabricated knockdown roll-out formwork for support on height and level adjustable screw jacks having heads including rollers defining a roll-out path and friction shoes adjustable to support said formwork above said rollers a predetermined distance is said path, said formwork comprising:
  - parallel spaced metal beams resting on said jacks and having coplanar head and bottom flanges, each beam having a nailable header of substantial thickness secured to the upper face of its head flange and a side strip of nailable material spaced above the bottom flanges and secured to the beams on facing sides of the two beams, said side strip having a horizontal thickness substantially coextensive with the lateral extension of each head flange to define with the headers vertical parallel planes;
  - hanger means spaced along the headers in manner facing each other in pairs and having horizontal portions releasably secured against the top surfaces of the respective headers and vertical flanges lying in one of said vertical planes, and hanger means including depending stirrup members with upper portions secured to said vertical flanges and horizontal strap means secured to lower portions thereof and releasably fastened to said side strip;
  - laminated wood joist means defining nailable head and bottom rails interconnected by a web and having a height greater than the vertical depth of said stirrup members to locate the head rails a substantial distance above said head flange with the lower rail located well above the lower flange;
  - means including bolts releasably securing the ends of said joist means between the sides of the stirrup members against relative tension and compression forces exerted between said beams and said joist means; and
  - plywood panel means secured to the head rails of said joist means to support poured concrete for a floor slab and to brace said formwork against horizontal strains.
2. The construction defined in claim 1 in which said joist means including said joist rails on opposite sides of the web engage the sides of said stirrup member under compression and have aperture means therethrough for the bolt means arranged equidistant from said rails for inverted reuse of the joist means in said stirrup members.
3. The construction defined in claim 2 in which said joist means are square at their ends and collectively engage said headers and strips to plumb the beams and support them against rotation under load as they rest upon the screw jack heads and when the formwork is supported by crane at formwork corners.
4. The construction defined in claim 2 in which said filler blocks and rails at the joists include plywood panel elements extending across said wood headers and are supported in abutting relation with said plywood panel means by said filler blocks and rail ends of said joists.
5. A flying form comprising:

a pair of parallel spaced metal beams disposed with parallel flanges along the head and bottom of their webs, respectively;

a wood header of substantial thickness rigidly secured to the upper face of the head flange and colevel wood strips secured a spaced distance above the bottom flange against the facing sides of said beam webs, said strips having a horizontal thickness substantially equal to the width of each head flange to define with the head flanges a pair of vertical parallel planes; hanger means spaced along the tops of the wood headers facing each other in pairs and each having horizontal portions releasably secured against the top surface of the headers and a vertical portion lying in one of said vertical planes, said hanger means including depending stirrup members with upper edge portions secured to said vertical portion, and strap means secured to the lower edges of the stirrup member and releasably fastened against the side strip;

20 laminated wood joists each having a head rail and bottom rail interconnected by a web and of a height greater than the depth of said stirrup members whereby the head rail is located a substantial distance above the wood header with the lower rail well above the lower flange;

means releasably securing the ends of each joist between the sides of a stirrup member including filler blocks extending from rail to rail at both ends and on both sides of the web filling the spaces between the web and stirrup; and

clamping means interconnecting the stirrup members and said blocks and web in place against compression and tension forces exerted between the metal beams and the joists.

6. The flying form defined in claim 5 including veneer panel forming a flooring and secured to the head rails for bracing said beams and joists against distortion from a geometric squareness.

7. In the construction of a building having at least 40 three parallel pairs of columns the combination of formwork roll-out support means on opposite sides of the central pair of columns and opposing pairs of roll-out support means on the facing sides on each of the two outer pairs of columns including screw jacks supporting rollers at a predetermined level with their axes paralleled in four pairs defining two paralleled formwork roll-out paths;

a pair of parallel spaced metal beams having top and bottom flange means disposed at the sides of each roll-out path resting on said respective rollers; wood headers secured to the top flanges of said beams;

hanger means spaced along the tops of said wood headers extending towards each other in spaced pairs and having horizontal flanges secured to the top flange means with stirrup members depending therefrom; joist means terminally supported within said stirrup means between each pair of beams with their upper edges disposed colevel within a limited height above said headers, and defining a space between said roll-out paths and intermediate said pair of columns;

veneer panel means secured and marginally terminating within a spaced distance related to the end of said joists;

means bridging said space and above the adjacent joist means including panel means carried thereby colevel with said coextensive veneer panel means; and

means for lowering one of said adjacent beams to increase the space between the tops thereof to release the space bridging means from the form support on one side for its removal downwardly from the form support on its other side.

8. In the construction of a building having at least three parallel pairs of columns with formwork support means on opposite sides of the columns of the central pair of columns and on the sides of the two outer pairs 10 of rollers where they face the central pair of columns, said supporting means including screw jacks, supporting rollers at a predetermined level with their axes parallel in four pairs defining two parallel formwork roll-out paths; the combination of

15 a pair of parallel spaced beams disposed at the sides of each roll-out path resting on said respective rollers; nailable members defining the tops of said beams; support means secured in spaced relation along the tops of said members and extending towards each other in spaced pairs bordering each of said paths and having depending stirrup means;

joist means terminally supported in said stirrup means between each pair of support means with their upper edges disposed above the level of said members, said beams defining open space between said roll-out paths and intermediate the columns of said central pair of columns;

panel means secured to said joists and marginally terminating coextensively a spaced distance related to the end of said joists and said open space between said roll-out paths;

means bridging said open space above the adjacent headers including secondary panel means carried by the beams colevel with said coextensive panel means; and

means for lowering at least one of said space defining beams to release the bridging means for movement downwardly from its supported position for removal and reuse.

9. The construction defined in claim 8 in which said secondary panel means of said space bridging means is supported on the adjacent ends of the joists bordering said space.

10. The construction defined in claim 8 in which said secondary panel means includes a frame spanning said space resting on the adjacent members and supporting said coextensive panel means.

11. A roll-out flying form comprising parallel spaced metal beams having facing channels defined by horizontal head and bottom flanges, each beam having a nailable header secured to the upper face of the head flange marginally coextensive with said head flange edges and a nailable strip spaced substantially above the bottom flange and having a horizontal thickness disposing its exposed face in vertically co-planar relationship with said header edge,

hanger means correspondingly spaced along the tops of the headers facing each other in pairs and having horizontal portions releasably secured against the tops of the headers and vertical flanges lying in one of said vertical planes, said hanger means including members with upper portions secured to the flanges and a strap member secured to the lower end thereof releasably fastened to said nailable strip,

a plurality of laminated wood joist means having head and bottom rails interconnected by a web and having a height greater than the depth of said hanger mem-

bers whereby the head rail is located a substantial distance above said head flange and the lower rail is well above the bottom flange, and means releasably securing the ends of said joists between the sides of the hanger members under compression and tension forces including blocks at both ends of the web filling the space between said head and bottom rails,

said releasable securing means including securement elements extending through said blocks, said web and the sides of said stirrup member, with said lower rail endwise positioned by said strap and strip.

12. In a knockdown flying form having spaced metal beams disposed with parallel webs and their respective head flanges disposed co-planar with spaced hangers secured to and depending from nailable headers secured to the respective head flanges and from nailable strips secured to the respective webs, said hangers having members having parallel sides disposed in vertical parallel orientation, in combination therewith,

laminated wood joists cross-sectionally having an "I" configuration of a greater height than that of the members and terminally resting in said members to plumb and space said metal beams throughout their length,

said joists having spaced nail receivable rails interconnected by a web and symmetrically invertable for either rail to serve as the top rail and including filler blocks extending from rail to rail at both ends on both sides of the web filling the spaces between the web and stirrup, and

fastening means interconnecting the stirrup members and said blocks and webs to secure them in place against compression and tension forces occurring between the metal beams and the joists including aperture means through said blocks and web.

13. A prefabricated knockdown roll-out formwork

comprising:

parallel spaced metal beams having co-planar head and bottom flanges, each beam having a header of substantial thickness secured to the upper face of its head flange and a nailable side strip secured to the beam above its bottom flange on facing sides of the two beams, said side strip having a horizontal thickness substantially coextensive with the width of each header flange to define with the headers vertical parallel planes;

means spaced along the headers facing each other in pairs and having portions releasably secured to the headers with a vertical portion lying in one of said vertical planes including depending support members with upper portions secured to said vertical portions and lower portions thereof fastened to said side strip; joist means defining nailable head and bottom rails interconnected by a web and having a height greater than the depth of said support members to locate the head rail an appreciable distance above said head flanges with the lower rail located well above the lower flange;

means releasably securing the ends of said joist means to said support members against relative tension and compression forces exerted between said beams and said joist means; and

plywood panel means secured to the head rails of said joist means to support poured cement for a floor slab and to brace said formwork against horizontal strains.

14. The device defined in claim 13 in which said metal beams have channels along their sides opposite to said spaced means within which to accommodate such spaced means on another beam in nesting relation when said beams are side-by-side to protect said spaced means from damage during storage and transportation.
